Atty.

UNITED STATES PATENT OFFICE.

JOSEPH L. DONAT, OF CHICAGO, ILLINOIS.

HEAT-RADIATING DEVICE.

Application filed March 3, 1923. Serial No. 622,667.

To all whom it may concern:

Be it known that I, JOSEPH L. DONAT, a citizen of the United States, and a resident of the city of Chicago, in the county of Cook and State of Illinois, have invented certain new and useful Improvements in a Heat-Radiating Device; and I do hereby declare that the following is a full, clear, and exact description of the same, reference being had to the accompanying drawings, and to the numerals of reference marked thereon, which form a part of this specification.

This invention relates to heating devices, more particularly for household purposes.

It frequently happens that one or more of the rooms in a house are insufficiently heated. Moreover, it is often the case that a chimney passes through such room up which chimney a large amount of heat escapes.

One of the principal objects of the present invention is to provide means for utilizing a part of this heat which now goes to waste for heating the air in a room.

Another object of the invention is to provide means for varying the amount of heat transmitted from the chimney gases to the room.

20 A further object of the invention is to provide an improved form of radiator.

Other and further important objects of this invention will be apparent from the disclosures in the specification and drawings.

The invention (in a preferred form) is illustrated in the drawings and hereinafter more fully described.

On the drawings:

40 Figure 1 is a side elevation of a heating device embodying the present improvements.

Figure 2 is a section on the line 2—2 of Figure 1.

45 Figure 3 is a section on the line 3—3 of Figure 2.

Figure 4 is a vertical section through a portion of a modified form of heater.

As shown on the drawings:

50 An entire section of the brick work (not shown) of the chimney, is removed for the insertion in its place of the radiator.

The radiator is preferably formed, as shown, of a plurality of sections, 6, each comprising a central passage 7 in substantial register with the passage through the

chimney proper and four passages 8 therearound.

As many sections are used as may be desired. Thus where only a small room is 60 to be heated only two sections may be provided as shown. For a large room, three or more may be employed.

The walls 9 of the central passage in the bottom section are cut away, as at 10, while 65 the side walls 9 of the top section are cut away, as at 11, to enable the chimney gases to flow outwardly under the walls 9, through the passages 8 and then inwardly into the chimney flue at the top of the radiator. 70

Since the central passage 7 is in substantial register with the passage through adjacent sections of the chimney, the hot gases will normally pass chiefly through the passage 7 and only to a very limited 75 extent through the passages 8. Under these circumstances little heat will be radiated into the room. To increase and control the flow of gases through the passages 8, a damper 12 is provided in the central passage 7. This damper is mounted upon a bar 13 provided with a handle 14 by which its position may be adjusted. When the damper is closed all of the gases are compelled to flow through the passages 8. In 80 the modified form of construction shown in Figure 4, the central passage is permanently closed by a plate or diaphragm 20.

The outer passages 8 are formed by the walls 9, continuations or extensions 15 of 90 these walls and radiating walls 16. In each corner between adjacent walls 15 are arranged piers 17 of masonry.

To enable a tight joint to be made between the piers and the walls 15 the latter 95 are grooved vertically, as at 21, for the reception of the grouting 22.

The various sections are secured to each other by means of lugs 23 in the corner between the walls 15. These lugs are attached 100 to each other by bolts 24.

At the bottom of the lower section and at the top of the higher section, the side walls 16 are extended inwardly to form a base 25 which may rest upon the brickwork 105 and a platform 26 respectively to support the brickwork of the upper part of the chimney. To increase the effectiveness of the walls 16 as heat radiating surfaces, a series of cones 18 may be formed therein 110 which greatly increase the heat radiating surface.

In front of each wall 16 is a grid 19 which prevents a person from accidentally coming in contact with the highly heated surface of the radiator proper.

I am aware that numerous details of construction may be varied through a wide range without departing from the principles of this invention, and I therefore do not purpose limiting the patent granted 10 otherwise than necessitated by the prior art.

I claim as my invention:

1. A heat radiating device adapted to replace a section of a chimney, masonry piers at each corner of the radiating device extending between the portions of the chimney so separated, and heat radiating surfaces arranged between said piers.
- 15 2. A heat radiating device adapted to replace a section of a chimney and having a

central rectangular flue providing a normally unobstructed straight passage for the chimney gases, passages adjacent each side of said flue, heat radiating surfaces each forming one wall of one of said passages, means for obstructing the flow of such gases through said flue to deflect such gases through said passages, and a masonry pier at each corner of the heating device extending between the portions of the chimney so separated.

In testimony whereof I have hereunto subscribed my name in the presence of two subscribing witnesses.

JOSEPH L. DONAT.
